Application September 19, 1945; Serial No. 617,203

14 Claims. (Cl. 262—28)

1

This invention relates to cuttings conveyor mechanism and more particularly to an improved reversible cuttings conveyor mechanism adapted for association with a reversible coal cutting machine for removing the cuttings from the vicinity of the cutter chain and for discharging the cuttings from the rear end of the machine during either direction of cutting.

In coal cutting machines of the longwall type or the shortwall type either of which slides on its own bottom directly over the floor of a mine during the cutting operation, the kerf cutting mechanism is usually reversible and the flexible feeding means of the machine is usually reversible so that horizontal kerfs may be cut near the floor level in either of opposite directions, and reversal of the machine is usually effected by reversing the machine motor. In such coal cutting machines, the cutter chain of the kerf cutting mechanism brings back the cuttings from the kerf and discharges the cuttings at the rear end of the machine, and it is desirable in such machines, mechanically to convey the cuttings from the vicinity of the cutter chain and mechanically to discharge the cuttings in a rearward direction from the machine to prevent the cuttings from piling up around the machine at the rear end of the cutting mechanism in such manner as to hinder the proper operation of the cutting mechanism. Such mechanical conveying means is usually attached to the rear end of the coal cutting machine and is preferably reversible so that it may operate to convey away the cuttings irrespective of the direction in which the machine is cutting. Such conveying mechanism must be efficient in operation and rugged in design and must be capable of operation over long periods of time without undue attention. Also such conveying mechanism must be readily detachable and readily reversible, and capable of being driven by an element of the coal cutting machine.

An object of the present invention is to provide an improved cuttings conveyor mechanism. Another object is to provide an improved reversible cuttings conveyor mechanism adapted for association with a reversible coal cutting machine whereby the cuttings may be removed from the vicinity of the cutter chain and discharged from the machine irrespective of the direction in which the machine is operating. A further object is to provide an improved cuttings conveyor mechanism capable of reverse operation by a simple transposition of parts. A still further object is to provide an improved re-

2

versible cuttings conveyor mechanism embodying a revoluble disk having a crank and a transposable pusher arm associated with said disk and actuated by said crank and having improved mounting means whereby the pusher arm may be transposed into reversed positions with respect to the disk whereby the arm may remove the cuttings from the disk irrespective of the direction in which the disk revolves. Still another object is to provide an improved reversible conveyor mechanism embodying a reversible crank disk and a swingable pusher arm actuated thereby and embodying means whereby the arm may be mounted in reversed positions with respect to the disk to enable discharge of the cuttings irrespective of the direction in which the disk is rotated. A still further object is to provide an improved interchangeable pusher arm and guard structure associated with a reversible conveyor disk. A further object is to provide an improved cuttings conveyor mechanism which is relatively simple and rugged in design and foolproof in operation, capable of operating for long periods of time without undue attention, and which may be readily reversed by a simple transposition of parts. These and other objects and advantages of the invention will, however, hereinafter more fully appear.

In the accompanying drawings there are shown for purposes of illustration several forms which the invention may assume in practice.

In these drawings:

Fig. 1 is a plan view of a longwall coal cutting machine with which an illustrative form of the improved cuttings conveyor mechanism is associated.

Fig. 2 is a side elevational view of the coal cutting machine and conveyor mechanism shown in Fig. 1.

Fig. 3 is an enlarged vertical view taken substantially on line 3—3 of Fig. 1.

Fig. 4 is an enlarged horizontal sectional view taken substantially on line 4—4 of Fig. 2.

Fig. 5 is a detail sectional view taken on line 5—5 of Fig. 4.

Fig. 6 is a horizontal sectional view similar to Fig. 4, showing the parts in reversed position.

Fig. 7 is a horizontal sectional view similar to Fig. 4, illustrating a modified form of conveyor mechanism.

Fig. 8 is a plan view of a shortwall coal cutting machine equipped with a further modified form of conveyor mechanism.

Fig. 9 is an enlarged vertical sectional view taken substantially on line 9—9 of Fig. 8.

Fig. 10 is a horizontal sectional view taken substantially on line 10—10 of Fig. 9.

Fig. 11 is a detail horizontal sectional view taken on line 11—11 of Fig. 9.

In the illustrative embodiment of the invention shown in Figs. 1 to 5 inclusive, the improved cuttings conveyor mechanism, generally designated 1, is shown associated with a conventional longwall coal cutting machine of the flexibly fed floor type, generally designated 2. The coal cutting machine 2 may be similar to that disclosed in the Richards Patent No. 2,262,048, granted November 11, 1941, and comprises an elongated relatively low and narrow machine frame 3 slidable on its own bottom 4 directly on the floor of a mine. The machine frame carries centrally thereof a conventional reversible motor 5, and arranged on the frame in advance of the motor is a horizontal feed drum 6 on which a feed cable 7 is wound. The feed drum is operatively connected to the motor for driving thereof in a manner fully described in the patent above referred to. Pivottally mounted on the rearward portion of the machine frame, rearwardly of the motor, is an elongated plane cutter bar 8 having an endless cutter carrying chain 9 guided for circulation about its margin. The cutter chain is operatively connected to the motor through bevel gears 10 and 11, spur gears 12 and 13, and a chain sprocket 14 connectable by a shiftable clutch 15 to a vertical shaft 16 in driving relation with the gear 13. The cutter bar 8 is carried by a hanger frame 17 swivelled on the machine frame about an axis coincident with the rotation of the shaft 16, and a shiftable latch 18 guided in a recess in the machine frame is receivable in appropriately locking recesses 19 in the hanger frame for locking the cutter bar in its different positions about its pivot, either lengthwise of the machine frame or in a right angle position at either side of the machine frame. The feed cable 7 is attachable to the hanger frame 17 to effect swinging of the cutter bar about its pivot. When the cutter bar is swung from the full line position shown in Fig. 1 into the opposite right angle position indicated in dotted lines in that figure to effect reverse cutting, it is necessary to reverse the motor 5, rewind the feed cable on the feed drum and reverse the position of the cutters on the cutter chain. This reversible cutting feature is common in longwall coal cutting machines and is fully described in the above mentioned Richards patent.

As is also fully described in the patent above referred to, during the making of a horizontal cut in the coal with the coal cutting machine located near the coal face, the cutter bar 8 may be swung by the feed cable 7 horizontally from a position extending lengthwise of the machine frame to the right angle position shown in full lines in Fig. 1, or to the dotted line position shown in that figure, to effect sumping of the cutter bar beneath the coal, and the cutter bar is thereafter locked to the machine frame by the latch 18. It will be understood that during the swinging movement of the cutter bar during the sumping operation, the cuttings conveying mechanism 1 is detached from the coal cutting machine. When the cutter bar is locked in a right angle position at either side of the machine frame and the cutter bar is sumped beneath the coal, the feed cable may be detached from the cutter bar hanger 17 and extended, as shown in full lines in Fig. 1, longitudinally in a forward direction and attached at its free end to an anchor jack located in adjacency

5 to the coal face in advance of the cutting machine. The cuttings conveying mechanism 1 is then attached to the rear end of the machine frame at the trailing side of the cutter bar in the manner shown in Figs. 1 and 2 and as the cutter chain 9 is rapidly circulated about the cutter bar and the feed cable 7 is wound in by the feed drum, the cutting machine is fed bodily in a forward direction along the coal face to make a horizontal cut in the coal near the floor level. During the making of the cut, the cuttings created by the cutters of the cutter chain and moved back from the kerf by the cutter chain will be, to a large extent, removed by the conveying mechanism from the vicinity of the cutter chain and discharged rearwardly from the machine.

10 The cuttings conveying mechanism 1 comprises a casing to enclose the working parts, provided with any appropriate means for its convenient attachment to the rear end of the machine frame of the cutting machine. As shown herein, a detachable top plate 20 of the machine frame has an overhanging rearward portion to the bottom and at the sides of which are secured 15 brackets 21, provided with longitudinal guideways 22 for receiving parallel lateral guides 23 on the conveyor casing. The conveyor casing is movable forwardly along the bracket guideways into abutting relation at 24 with a plane vertical abutment surface on the machine frame of the cutting machine, and when the conveyor casing is so positioned against the machine frame, the bottom of the conveyor casing abuts at 25 with the rear edge of a bottom plate 26 of the machine frame. 20 20 The conveyor casing comprises a bottom plate 27 which slides over the mine floor and it is the rear edge of this plate which abuts at 25 the bottom plate 26. The bottom plate 27 is secured by upright tie bolts 28 to an upper casing 29 on which 25 the lateral guides 23 are formed. The upper part 29 of the conveyor casing has lateral arm-like projections 30 at the opposite sides thereof and these projections have slots 31 for receiving eye-bolts 32 on which are threaded adjustable wing nuts 33. These eye-bolts are pivotally mounted on vertical pivot pins 34 carried by the brackets 21, and are swingable horizontally about their pivots from their released dotted line position, shown in Fig. 1, to their operative full line position shown in that figure in engagement with the projection-slots 31, and when the wing nuts are tightened, the conveyor casing is clamped tightly against the rear end of the machine frame of the coal cutting machine. When the wing 30 nuts are loosened and the eye-bolts are swung outwardly to their released positions, the conveyor may be easily detached from the coal cutting machine simply by sliding the casing outwardly in a rearward direction.

35 The conveyor casing has a horizontal chamber which communicates at its forward side with a horizontal chamber 36 within the machine frame, and the cuttings brought back from the kerf by the cutter chain are received in the chamber 36 and the rapidly circulating cutter chain throws a large portion of the cuttings directly into the chamber 35 of the conveyor casing, as will be clearly apparent in Fig. 4. Arranged within the casing chamber 35 near the bottom of the casing is a circular table or disk 37 which is mounted for rotation about an upright axis, and has its marginal portion at its forward side underlying the orbital path of the cutters of the return run of the cutter chain. The structure of 40 the conveyor mechanism thus far described is

generally similar to that disclosed in the Richards Patent No. 2,278,119, granted March 31, 1942.

Now referring to the improved conveyor structure of the present invention, it will be noted that the revolving disk or table 37 has an upstanding crank or eccentric portion 38, and secured as by screws 39 to the upper surface of the crank is a circular plate 40 having an offset upstanding hollow shaft 41 alined with the axis of table rotation. The shaft 41 is journaled in a bearing supported within the upper part 29 of the conveyor casing, and is keyed to a vertical shaft 42 passing through a vertical bore in the crank 38 and journaled at its lower end beneath the table in a bearing supported within the bottom plate 27 of the conveyor casing. A dirt ring 43, arranged in grooves in the bottom of the disk 37 and the top of the bottom plate 27, serves to prevent access of dirt to the lower bearing. Surrounding the crank 38 of the disk are bearing sleeves 44 on which is pivotally mounted an oscillatory arm or link 45 which extends vertically between the top of the disk 37 and the lower surface of the plate 40. This arm or link 45 has a radially projecting lug 46 to which are pivotally connected by a detachable vertical pivot 47 spaced lugs on one end of a horizontal swingable pusher arm 48. The pusher arm overlies the disk and extends along the open side of the casing-chamber 35 at the prop side of the coal cutting machine opposite to that from which the cutter bar projects, as shown in Fig. 4, and is pivotally mounted on a detachable vertical pivot pin 49 supported at the outer side of the conveyor casing. The pusher arm is so arranged that when the disk 37 is rotated, the crank 38 and the arm or link 45 move in an orbital path to engage the cuttings in the casing-chamber and to move the cuttings rearwardly through the casing to discharge at the rear side of the casing; and the cuttings which move in back of the pusher arm 48 are forced laterally, as the pusher arm is swung by the crank, into the bottom of the pile of cuttings by the pusher arm. The crank 38 is spaced inwardly toward the center of the disk 37 from the disk periphery so that the marginal portion of the disk which passes beneath the cutter chain is located outwardly beyond the crank, and the arm or link 45 is arranged outside the cutter chain orbit so that it clears the cutters as the disk revolves. The open side of the casing-chamber 35 near the coal face is closed by a transposable guard plate 50 held at its forward end in position on the conveyor casing by a detachable vertical pin 51, and engaging at its grooved rear end at 52 one of the tie bolts 28. The pins 49 and 51 are identical and are so located on the conveyor casing that the guard plate 50 and the pusher arm 48 may be interchanged to enable reverse operation of the conveyor in the manner shown in Fig. 6. Of course the conveyor mechanism is detached from the frame of the coal cutting machine when the cutter bar 8 is swung horizontally from its right angle position shown in Fig. 4 to the opposite right angle position shown in Fig. 6. The outer prop side of the cuttings-receiving chamber 36 of the coal cutting machine is closed by a detachable guard 53 which engages at its grooved rear end at 54 one of the tie bolts 28 and is firmly held in position by screws 55 engaging its front end, and this guard confines the cuttings in the cuttings-receiving chamber 36 and directs them toward the chamber 35 of the conveyor casing. During the reverse cutting operation, the guard 53 may be transposed to the op-

posite side of the coal cutting machine as shown in Fig. 6.

Now referring to the driving means for the conveyor disk or table 37, crank 38 and pusher arm 48, it will be noted that keyed to the upper end of the cutter chain drive shaft 16, as shown in Fig. 3, is a spur gear 56. The spur gear 56 meshes with a spur gear 57, which in turn meshes with and drives a spur gear 58. The upper end of the shaft 16 which carries the spur gear 56 and the vertical shafts 59 and 60 which carry the spur gears 57 and 58 respectively, are suitably journaled in bearings supported within the top plate 20 of the coal cutting machine. The shaft 60 of the gear 58 is also journaled in a lower bearing supported by a bracket 61 suitably secured to the rear end of the machine frame, and keyed to the lower end of the shaft 60 is a spur gear 62 which meshes with and drives a spur gear 63. The gear 63 is connected by a friction clutch 64 to the upper end of the disk drive shaft 42. The clutch 64 is of a conventional design and is spring-loaded and is set to slip upon overload so that in the event the conveyor becomes overloaded, the clutch will automatically slip to prevent damage to the conveyor parts. It is evident that the conveyor is driven by the machine motor 5 and when the machine motor is reversed to effect reversal of the coal cutting machine, the conveyor is concurrently reversed. The disk or table 37 revolves in the direction opposite to the direction of rotation of the chain drive sprocket 14 so that the cutter chain 9, as it passes around the chain sprocket at the rear end of the cutter bar, throws the cuttings onto the disk, and the disk moves the cuttings out of the path of the return run of the cutter chain and into the casing chamber.

In the modified construction shown in Fig. 7, the conveyor casing 70 is of box-like construction and has its horizontal chamber 35' closed by vertical side walls 71 and the rear side of the casing is open at 72. A transposable pusher arm 48' extends transversely of the conveyor casing partially across the rear opening 72 and is pivoted on a detachable vertical pivot pin 73 at the outer side of the rear portion of the conveyor casing. As the disk 37 revolves, the crank actuates the link 45' to move the cuttings rearwardly through the casing chamber to discharge at the rear end of the coal cutting machine and the pusher arm 48' forces the cuttings rearwardly into the bottom of the pile of cuttings in the machine track. A detachable pin 74 is located at the opposite side of the rear portion of the conveyor casing so that the position of the pusher arm 48' may be reversed during reverse operation of the conveyor. In this instance, the conveyor casing is attached to the rear end of the machine frame of the coal cutting machine by vertical pins 75 and the rear end of the transposable guard 53', which closes the outer side of the cuttings-receiving chamber 36, is fitted in a vertical groove 76 in the conveyor casing. Otherwise, this form is similar to that above described.

In the modified embodiment shown in Figs. 8 to 11 inclusive, a cuttings conveyor mechanism, generally designated 80, is associated with a conventional shortwall coal cutting machine, generally designated 81. This coal cutting machine may be of the same general character as that disclosed in the Joy and Simmons Patent 2,131,751, granted September 27, 1938. The coal cut-

ting machine 81 comprises a machine frame 82 slidable on its bottom 83 directly on the mine floor. Extending centrally forwardly lengthwise of the machine frame in rigid relation therewith is an elongated plane cutter bar 84 having a cutter carrying cutter chain 85 guided for circulation about its margin. The rearward portion of the cutter bar is arranged in a horizontal bottom chamber 86 extending longitudinally within the lower portion of the machine frame so that the cuttings brought back from the kerf by the cutter chain are moved rearwardly through the chamber 86 to discharge at the rear end of the machine. The cutter chain may be driven from a motor 87 at the forward end of the machine frame above the cutter bar through transmission connections fully described in the above mentioned Joy and Simmons patent and including a cutter chain drive sprocket 88 located at the rear end of the machine frame and which engages and drives the cutter chain. For feeding the machine during the cutting operation, there are provided feeding and controlling drums 89 and 90 arranged at opposite sides of the rearward portion of the machine frame and on which feeding and controlling cables 91 and 92 are respectively wound. During the feeding operation, the free ends of these cables are attached to anchor jacks respectively located at the coal face and the rib of the room of a mine and as the cables are wound in by the drums, the cutter bar may be sumped beneath the coal at one rib, thereafter be fed transversely across the coal face to cut a horizontal kerf beneath the coal, and finally the cutter bar may be withdrawn from the face at the opposite rib. The feeding drum 89 effects feeding of the machine and the controlling drum 90 controls the angle of the machine with respect to the coal face during the coal cutting operation in a manner well known to those skilled in the art. By reversing the motor 87, rewinding the cables on the drums and reversing the position of the cutters on the cutter chain, the machine may cut in the reverse direction. During either direction of cutting, the cuttings created by the cutters of the cutter chain are carried back from the kerf through the chamber 86 extending through the lower portion of the machine to discharge at the rear end of the machine.

The improved cuttings conveyor mechanism 80 is attached to the rear end of the coal cutting machine, rearwardly of the chain sprocket 88, and is arranged in such a manner that its conveying devices remove the cuttings from the vicinity of the rearward portion of the cutter chain at the rear end of the chamber 86 and convey the cuttings to discharge rearwardly of the machine out of the machine path. The conveyor mechanism comprises a box-like lower casing 93 slidable on its bottom on the mine floor and having forwardly projecting side portions 94 secured by screws 95 to the sides of the machine frame of the coal cutting machine. Mounted on the top of the lower casing portion 93 is an upper housing 96 having a detachable upper portion 97. The lower casing portion 93 has a horizontal chamber 98 which, when the conveyor casing is attached to the machine frame, communicates directly with the rear end of the chamber 86 so that the cuttings moved rearward by the cutter chain in the chamber 86 are discharged into the chamber. Arranged in the casing at the bottom of the chamber 98 is a circular disk or table 37' having its forward marginal portion arranged near the outer boundary

of the orbit of the cutters of the cutter chain. This disk has an upstanding crank or eccentric portion 38' to which an oscillatory arm or link 45'' is pivotally connected, and this link has a projecting lug pivotally connected at 47' to one end of a transposable pusher arm 48''. The pusher arm is pivotally mounted on a detachable pivot pin 49' at the side of the conveyor casing at the receding side of the coal cutting machine. The side of the casing chamber 93 at the advancing side of the coal cutting machine is closed by a transposable guard 50' secured by a detachable pin 51' at its forward end to the conveyor casing. As in the embodiment shown in Fig. 6, the grooved rear end of the guard engages at 52' one of the tie bolts 28'. The pusher arm 48'' is so arranged that when the disk 37' is rotated, the crank 38' and arm or link 45'' move in an orbital path to engage the cuttings in the casing chamber and to move the cuttings rearwardly through the casing to discharge at the rear side of the casing; and the cuttings which move in back of the pusher arm 48'' are forced laterally into the bottom of the pile of cuttings by the pusher arm. As in other embodiments, the pins 49' and 51' are identical and are so located that the guard and pusher arm may be interchanged to enable reverse operation of the conveyor.

In this illustrative embodiment, the driving means for the conveyor disk, crank and pusher arm comprises a shaft 99 (Fig. 9) extending longitudinally within the machine frame and whose direction of rotation is reversed whenever the motor 87 is reversed to effect reversal of the coal cutting machine. The shaft 99 is clutched at 100 at its rear end to the hub of a cone 101 of a frictional cone clutch similar to the clutch 64 above described. The clutch cone is spring-loaded and held in frictional engagement with a clutch member 102 formed on a longitudinal shaft 103, the latter being clutched at 104 to an aligned shaft 105. The shaft 105 is suitably journaled within the upper housing 96 and has formed thereon a bevel gear 106 meshing with a bevel gear 107 journaled on a vertical shaft 108, the latter in turn being suitably journaled within the housing. The gear 107 is connectable by a shiftable clutch member 109 to the shaft 108 and formed on the lower end of the shaft is a spur gear 110 meshing with a spur gear 111 (see also Fig. 11). The gear 111 meshes with and drives a spur gear 112 which is secured to the vertical drive shaft 42' for the revolving disk 37'. It is evident that the disk is driven through the connections above described in a direction opposite to the direction of rotation of the cutter chain drive sprocket 88 and the cutter chain, as it passes around the chain sprocket 88 throws the cuttings onto the conveyor disk. It will be noted that the disk, crank and arms are so arranged that a large portion of the cuttings is discharged laterally from the casing, a feature of importance when the roof props are located close to the rear end of the coal cutting machine.

As a result of this invention, an improved cuttings conveyor mechanism is provided, adapted for attachment to a conventional coal cutting machine for effectually removing the cuttings from adjacency to the cutter chain and for discharging the cuttings rearwardly from the machine. By the provision of the mounting for the transposable pusher arm, it is possible, by a simple transposition of parts, to effect operation of the cuttings conveyor mechanism selectively in either of opposite directions. By the provision of

but a single reversible conveyor disk arranged in the manner disclosed and the particular arrangement of the crank and arms, not only is a relatively simple and rugged structure attained, but also conveying of the cuttings from the machine is effected in an extremely efficient manner. By the provision of the driving means disclosed for the conveyor disk, reversal of the disk is effected whenever the machine motor is reversed to reverse the coal cutting machine. Other uses and advantages of the invention will be clearly apparent to those skilled in the art.

While there are in this application specifically described several forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A reversible cuttings conveying mechanism comprising, in combination, a casing having a chamber for receiving cuttings, a single reversible circular table journaled in said casing at the bottom of said chamber to revolve about an upright axis for moving the cuttings rearwardly in said chamber irrespective of the direction of table rotation, said table having an upstanding crank, transposable pusher-arm means actuated by said crank for removing the cuttings from said table during either direction of rotation thereof and for positively ejecting the cuttings from said casing, and supporting means on said casing for pivotally supporting said pusher-arm means in either of the transposed positions of said pusher-arm means.

2. A reversible cuttings conveyor mechanism adapted for association with a reversible coal cutting machine of the kind having a reversible endless circulating cutter chain, comprising a single reversible table journaled to revolve about an upright axis and having its peripheral portion adapted to lie close to the orbit of the cutter chain for removing the cuttings from the vicinity of the cutter chain irrespective of the direction of travel of the latter, said table having an upstanding crank the axis of which is spaced from the axis of rotation of said table, a transposable pusher arm overlying said table and actuated by said crank for positively moving the cuttings rearwardly with respect to said table, and mounting means for said pusher arm whereby the latter may be supported in reversed positions with respect to said table, said arm being mounted in one position with respect to said table during table rotation in one direction and mounted in a reversed position with respect to said table during table rotation in the opposite direction.

3. A reversible cuttings conveying mechanism adapted for association with a reversible coal cutting machine having a reversible endless circulating cutter chain comprising, in combination, a single reversible horizontal disk so arranged that its peripheral conveyor portion is adapted to run close to the cutter chain orbit for removing the cuttings from the vicinity of the cutter chain during either direction of travel of the latter, a reversible pusher arm transposable into reversed positions with respect to said disk for positively moving the cuttings laterally from said disk and arranged at one side of said disk during its operation, a transposable guard disposed at the other side of said disk for confining the cuttings there-

on, and mounting means for said arm and guard whereby the same may be interchangeably supported in either of their transposed positions with respect to said disk.

- 5 4. A reversible cuttings conveying mechanism adapted for attachment to a reversible coal cutting machine having a reversible endless circulating cutter chain comprising, in combination, a casing attachable to the coal cutting machine and having a chamber adapted to receive the cuttings discharged from the coal cutting machine, a reversible circular horizontal table arranged in said casing near the bottom of said chamber for moving the cuttings from the vicinity 10 of the cutter chain irrespective of the direction of operation of the cutting machine, said chamber having open sides, and said table having an upstanding crank, a pusher arm actuated by said crank and arranged at one open side of said chamber for removing said cuttings from said table and for positively ejecting the cuttings laterally from said casing, a guard closing the opposite open side of said chamber, said guard and said arm being interchangeable, and said casing having mounting means for said arm and guard for supporting the latter in either of the interchanged positions thereof.
- 15 5. A reversible cuttings conveying mechanism for a reversible coal cutting machine of the endless circulating reversible cutter chain type, the combination comprising a single reversible revolving table journaled for rotation about an upright axis and having a marginal portion adapted to lie close to the cutter chain for moving the cuttings from the vicinity of the cutter chain irrespective of the direction of travel of the latter, said table having an upstanding crank, a pusher arm overlying said table and actuated by said crank, and means whereby said arm may be 20 transposed into reversed positions with respect to said table so that said arm may remove the cuttings from said table during either direction of table rotation.
- 25 6. A reversible cuttings conveying mechanism comprising, in combination, a casing having a chamber for receiving cuttings and having closed sides and open ends, a single reversible circular table journaled in said casing at the bottom of said chamber to revolve about an upright axis 30 for moving the cuttings through said casing chamber, said table having an upstanding crank, transposable pusher-arm means extending transversely of said casing at the open rear end of said chamber for removing the cuttings from said table and for positively ejecting the cuttings 35 rearwardly from said casing, and supporting means on the rearward portion and at the opposite sides of said casing for pivotally supporting said pusher-arm means in either of the transposed positions thereof.
- 40 7. In a reversible cuttings conveying mechanism for a reversible coal cutting machine of the reversible endless circulating cutter chain type, the combination comprising a reversible rotary conveyor device adapted to operate in either of opposite directions in accordance with the direction of cutting of a coal cutting machine for removing the cuttings from the vicinity of the cutter chain of the cutting machine, said conveyor 45 device including a reversible horizontal disk journaled for rotation on an upright axis and having its marginal portion adapted to run close to the cutter chain orbit, transposable cuttings-ejector means operatively connected to said disk for actuation thereby and overlying said disk for re-
- 50 55 60 65 70 75

11

moving the cuttings from said disk and for positively ejecting the cuttings, and mounting means for said ejector means whereby the latter may be transposed into reversed positions with respect to said disk.

8. In a reversible cuttings conveying mechanism, the combination comprising a casing, a reversible cuttings conveying disk arranged in said casing to revolve on a vertical axis located midway between the sides of said casing and adapted to receive the cuttings discharged from a coal cutting machine during either direction of operation of the latter, said disk having a crank, a transposable pusher arm pivotally mounted on said casing and pivotally connected to said crank whereby said crank effects swinging of said arm during disk rotation, and means for pivotally mounting said arm on said casing selectively in either of its transposed positions whereby said arm may remove said cuttings from said disk during either direction of rotation of said disk.

9. In combination, a shortwall coal cutting machine including a frame having a motor thereon and a cutter bar extending forwardly lengthwise thereof, a cutter chain mounted on said cutter bar and extending rearwardly along said frame and below said motor and around a drive sprocket at the rear end, a driving connection between said motor and said sprocket providing for reverse driving of said sprocket and cutter chain whereby said machine may cut kerfs while feeding said cutter bar laterally in opposite directions, and reversible cuttings conveying mechanism mounted within the lateral confines of said frame and closely adjacent to the rear end of said cutter chain and operative to receive cuttings carried rearwardly by said cutter chain and adapted to discharge them from said machine for reverse operation thereof and reverse travel of said cutter chain, said cuttings conveying mechanism including a single horizontal disk rotating on an upright axis located midway between the sides of said frame, transposable cuttings-moving means operatively connected to said disk for actuation thereby for removing the cuttings from said disk and for positively ejecting the cuttings rearwardly out of the machine path, and mounting means for said cuttings-moving means for supporting the latter in either of the transposed positions, the aforescribed construction providing a compact shortwall type coal cutting machine.

10. The combination with a reversible shortwall coal cutting machine adapted to cut in either of opposite directions including a cutter bar connected to the front end of a frame adapted to rest on and slide over a mine floor when the machine is fed transversely of the cutter bar, and a reversible cutter chain on said cutter bar extending along the bottom of said machine to a chain drive sprocket adjacent the rear end thereof, of reversible cuttings conveying mechanism at the rear end of said cutting machine and rearwardly of said cutter chain and drive sprocket and in position to receive cuttings from said cutter chain irrespective of the direction of travel of the latter and move them in a direction away from the cutting machine, said cuttings conveying mechanism including a casing, a large circular reversible table mounted in said casing for rotation on an upright axis located midway between the sides of the machine, a transposable cuttings-moving member overlying said table and operatively connected to said table for actuation

12

thereby for moving the cuttings from said table irrespective of the direction of rotation of said table, and mounting means on said casing for supporting said cuttings-moving member in either of its transposed positions with respect to said table, said cuttings-moving member acting when in one position to move the cuttings laterally from said table when the machine is fed in one direction and said cuttings-moving member when transposed into its reversed position acting to move the cuttings laterally from said table in the opposite direction when the machine is fed in the opposite direction.

11. The combination with a reversible shortwall coal cutting machine adapted to cut in either of opposite directions including a cutter bar connected to the front end of a frame adapted to rest on and slide over a mine floor when the machine is fed transversely of the cutter bar, and a reversible cutter chain on said cutter bar extending along the bottom of said machine to a chain drive sprocket adjacent the rear end thereof, of reversible cuttings conveying mechanism at the rear end of said cutting machine and rearwardly of said cutter chain and said drive sprocket and in position to receive cuttings from said cutter chain irrespective of the direction of travel of the latter and move them in a direction away from the cutting machine, said cuttings conveying mechanism including transposable cuttings-moving means for ejecting the cuttings laterally at the receding side of the machine irrespective of the direction in which the machine is fed, and mounting means for said cuttings-moving means for supporting the latter in either of its transposed positions, said cuttings-moving means when in one position acting to eject the cuttings laterally in one direction when the machine is fed in one direction and said cuttings-moving means when in its transposed position acting to eject the cuttings laterally in the opposite direction when the machine is fed in the opposite direction.

12. A reversible cuttings conveying mechanism adapted for association with a reversible coal cutting machine of the kind having reversible orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine frame chamber, and cuttings moving means in said casing chamber for moving the cuttings rearwardly therein and for positively ejecting the cuttings therefrom, said cuttings moving means including a transposable cuttings-moving-and-ejecting element, means for pivotally mounting said cuttings-moving-and-ejecting element on said casing at one side of the latter in either of the transposed positions of said element, and said element when in either of its transposed positions projecting horizontally inwardly toward the opposite side of said casing, and means to which said element is operatively connectable in either of the transposed positions of said element for swinging said element horizontally back and forth on its pivotal mounting to cause said element to engage the cuttings and move the cuttings rearwardly in and eject the cuttings so moved from said casing chamber.

13. A reversible cuttings conveying mechanism comprising, in combination, a casing having a chamber for receiving cuttings, a reversible circu-

13

lar table arranged at the bottom of said chamber and journaled in said casing to revolve about an upright axis, a detachable oscillatory pusher arm pivoted at one end on said casing and transposable into reversed inverted positions with respect to said table, said pusher arm being operatively connected to said table for oscillation thereby and serving to move the cuttings on said table laterally from said casing irrespective of the direction of table rotation, and pivotal mounting means at the opposite sides of said casing for pivotally supporting said pusher arm in its reversed transposed positions with respect to said table, said mounting means including supporting portions and cooperating pivot elements at the sides of said casing with which the pivoted end of said pusher arm is selectively engageable.

14. A reversible cuttings conveying mechanism comprising, in combination, a casing having a chamber for receiving cuttings and having open sides, a reversible circular table arranged at the bottom of said chamber and journaled in said casing to revolve about an upright axis, a detachable guard closing an open side of said casing for confining the cuttings on said table, a detachable oscillatory pusher arm pivotally mounted on said casing in the other open side thereof and

14

operatively connected to said table for oscillation thereby, said pusher arm serving to move the cuttings on said table laterally through the open side of the casing in which the arm is mounted, 5 and mounting means at the opposite sides of said casing for said guard and pusher arm whereby the same may be interchangeably supported in inverted reversed positions with respect to said table respectively to confine the cuttings and to enable removal of the cuttings during either direction of table rotation, said mounting means including supporting portions common to said guard and pusher arm and releasable supporting elements cooperating with said supporting portions and either adapted to serve as a guard-se- 10 curing element or an arm pivot element.
